UNITED STATES PATENT OFFICE.

GEORGE E. HALL, OF AKRON, OHIO.

METHOD OF MANUFACTURE OF RUBBER WATER-BOTTLES.

1,148,226.

Specification of Letters Patent. Patented July 27, 1915.

Application filed February 26, 1915. Serial No. 10,747.

To all whom it may concern:

Be it known that I, GEORGE E. HALL, citizen of the United States, residing at Akron, in the county of Summit and State 5 of Ohio, have invented certain new and useful Improvements in Methods of Manufacture of Rubber Water-Bottles, of which the following is a specification.

This invention relates to the manufacture 10 of rubber water bottles or bags, or vessels of a similar kind, and it has for its object to provide an improved process or method of making such bottles in such manner that they shall be practically seamless. For 15 many reasons it is desirable to avoid seams in such articles, but difficulty has been experienced in providing a method of making such a bottle which will permit the withdrawal of the core or mandrel, while preserving 20 a regular or symmetrical shape of the finished article.

The present invention provides a method whereby a seamless bottle can be made, of a graceful and symmetrical shape, and with 25 desirable reinforcement at the neck and shoulders of the bottle. The invention also provides an improved manner of attaching or placing the metal thimble in the neck.

In the accompanying drawings, Figure 1 30 is a front elevation showing the bottle or blank in its first condition. Fig. 2 is a similar view, showing the slot or opening through which the core is removed. Fig. 3 is a view of the finished bottle, partly broken 35 away showing the thimble applied.

Primarily, the body portion 6, the neck portion 7, the funnel portion 8, and the tabs 9 are molded in one piece, in a suitable mold, and over a suitable core or mandrel, corrugations 10 being formed on the inside of the neck portion.

In order to permit the core to be withdrawn, the neck and funnel portions of the blank are made in the form of two separate 45 flaps which are united or continuous at their lower or inner ends with the opposite sides of the body, but which are free or disconnected from each other above or beyond a slit or opening extending across the top 50 of the bottle at the points 11 at the shoulder of the bottle. In other words, instead of making the neck and funnel portions continuous and circular, they are split or left open at the edges, down to the points 11, as 55 illustrated in Fig. 2, thereby producing a

slit or opening at the top of the bottle of sufficient length to permit the withdrawal of the core through said opening by stretching the body at said opening and "stripping" the bottle off of the core. It should 60 also be stated that at the time the blank or body is made, as above indicated, each of the neck and funnel halves or parts 7 and 8 is provided along each edge with an extension or flange indicated at 12; also, each shoulder 65 of the body is provided with a flange 13 extending to the slit 11, for a purpose to be hereinafter described. The mold in which the blank is made as above described is suitably constructed for the above purpose, 70 and the resulting blank is seamless and is closed at all points except the elongated opening below the neck.

After the removal of the blank from the mold and from the core the metal thimble 75 or neck piece is applied. This is done by placing said thimble, which is indicated at 14, between the neck flaps 7, rubber gum or cement being first applied around the edges 12, as well as around the thimble and in the 80 corrugations 10, the thimble being corrugated accordingly to engage therewith. The neck parts being then closed against the thimble, the flanges or edges 12 are lapped and pinched or worked together, by hand, 85 to form the complete tube or funnel and to close the side openings or joints, thereby completing and forming the funnel, the neck around the thimble, and the portions at the base of the neck down to the points 11. It 90 is then necessary to place the article in a suitable vulcanizing mold for the purpose of vulcanizing the raw gum and cement used for the purpose of fastening the top flaps together, as explained above. When inserted in such a mold or press and suitable heat applied the joints are cured and united, making a practically one piece bottle. The flanges 13, on the shoulders of the bottle, are used in this vulcanizing step for the 100 purpose of being gripped by the vulcanizer parts while the vulcanizing operation is proceeding, otherwise the pressure incident to the vulcanization would tend to cause the bottle to slip out of position, but the invention can be realized without the use of such flanges 13 if a way can be found to otherwise hold the bottle in the vulcanizer while the joints are being cured. After the parts are 105 united and vulcanized as above described the 110

flanges 13 are trimmed off smooth, and the complete bottle remains, as illustrated in Fig. 3.

It will be observed that in addition to 5 providing a novel means for withdrawing the core at the top of the bottle, the invention provides an improved manner of placing and securing the neck thimble in 10 position and for reinforcing the bottle at 10 the part where it particularly needs it, that is, at the funnel, the neck, and the base of the neck, such reinforcement being provided by the lapped, cemented and vulcanized flanges 12.

15 What I claim as new is:

1. The method of making a rubber bottle or similar vessel, comprising molding the body and neck portions over a core, the neck portion being formed in two side parts with

20 an opening therebetween permitting withdrawal of the core, and uniting the edges of said parts, after removal of the core, to form the neck.

2. The method of making a rubber bottle or similar vessel, comprising molding the body and neck portions over a core, the neck portions being formed as two flaps or parts with separated edges extending to the shoulders of the bottle, withdrawing the core 25 through the opening between said parts, and then uniting said edges to form the neck.

3. The method of making a rubber bottle or similar vessel, comprising molding the body and neck in a single piece over a core, the neck portion being formed as two side flaps with extended flanges at the edges thereof, withdrawing the core through the 30 opening between said flaps, and then uniting the said flanges to form the neck.

4. The method of making a rubber bottle or similar vessel, comprising molding the body and neck portions in a single piece over a core, the neck portion being formed as two flaps separated at their edges, said separation extending outwardly into the 40 shoulders of the body, to form an opening for the withdrawal of the core, and said flaps having flanges at said edges, withdrawing the core through said opening, and then uniting and vulcanizing the 45 said flanges to form the neck and close the shoulder opening.

5. The method of making a rubber bottle or similar vessel, comprising molding the body and neck portions over a core, forming 50 the neck portion in two side parts with an opening therebetween, withdrawing the core through said opening, inserting a neck thimble between said side parts, and uniting and vulcanizing the edges of said parts, to 55 form the neck and hold the thimble in place.

6. The method of making a rubber bottle or similar vessel, comprising molding the body and neck portions over a core, forming the neck portion in two separate side 60 flaps with flanges at the edges thereof and transverse slits in the shoulders at the base of said flaps, withdrawing the core through the opening provided by said flaps and slits, and then uniting the flanges and closing the 65 slits by cementing and vulcanizing the 70 edges.

In testimony whereof, I affix my signature in presence of two witnesses.

GEORGE E. HALL.
